UNITED STATES PATENT OFFICE

SAMUEL G. MARTIN, OF WEST SOMERVILLE, MASSACHUSETTS, ASSIGNOR TO THE BARRETT COMPANY, A CORPORATION OF NEW JERSEY

CUTTER

Application filed September 25, 1923. Serial No. 664,667.

This invention relates to a device for cutting a long strip of material into predetermined lengths. It relates more particularly to cutting thin, narrow strips of metal such as galvanized iron, into uniform lengths for tying bundles of shingles or the like.

By this invention strips of different sorts may be automatically cut into uniform lengths without requiring close attention on 10 the part of the operator and when lengths of different sorts are to be cut, the device can be readily altered so as to obtain straps of the desired length all of which will be substantially uniform while the device is set 15 for cutting straps of that particular length. The invention will be understood from the description in connection with the drawings in which,

Figure 1 is a side view of the device; 20 Fig. 1^a is a detail of the pull rolls and the actuating mechanism therefor; Fig. 2 is a plan view of Fig. 1; Fig. 3 is a detail showing the knife and its operating mechanism; 25 Fig. 4 is a side view of a modification; Fig. 5 is a plan view of Fig. 4; Fig. 6 is a detail showing the pull rolls; Fig. 7 is a detail showing the cutter; and Fig. 8 is a detail showing the knife carrier. 30 In the drawings, reference characters 1 and 2 indicate a number of continuously operable pull rolls that are mounted so as to be in contact with each other. One of these rolls 2 may be mounted in the housing 3 which slides 35 in a guide 4 and a spring 5 is provided for pressing the roll 2 toward the roll 1. The roll 2 is carried on a shaft 6 which is provided with a driving motor 7 or a pulley that has a belt passing thereover from any convenient 40 source of power, not shown. The roll 1 may be carried by the shaft 8 which may have a gear 9 on the end thereof meshing with the gear 10 on the shaft 6. The shaft 6 also carries a pinion gear 11 which meshes with the 45 pinion gear 12 on the shaft 13. Mounted upon the shaft 13 are a series of sprockets 14 of different sizes. The shaft 15 is mounted parallel with the shaft 13 and carries a series of sprockets 16 which are driven from the 50 sprockets 14 by means of the chain belt 17.

The shaft 15 carries a wheel 18 upon the periphery of which may be mounted one or more strikers 19, the purpose of which will be explained below.

A guide 20 extends from near the roll 1 and 55 is provided with a groove 21 along its upper surface through which the strip is to be fed. A sprocket wheel 22 is mounted upon the shaft 6 and a shaft 25 which is parallel with the shaft 6 carries a corresponding sprocket 60 24 which is driven by means of the sprocket chain 23. The shaft 25 carries a continuously rotatable drive feed roll 26 which is slightly larger in diameter than the feed roll 1 so that the periphery thereof will travel at a 65 faster rate of speed than the periphery of the feed roll 1. A continuously rotatable pressure roll 27 is mounted in the housing below the roll 26 and is pressed upwardly thereagainst by means of the spring 28. Thus 70 rolls 26 and 27 are yieldingly pressed together and are adapted to slip on the material when the feed thereof is obstructed by the cutter 30 hereinafter described.

A bed plate 29 is located just beyond the 75 pull roll 26 and a knife or cutter 30 is provided to cooperate therewith to sever the material at the proper moment. The knife 30 is pivoted at 31 and a spring 32 under the other end thereof tends to keep the same in 80 its raised position.

The operation is as follows: The strip of material to be cut into predetermined lengths is first wound upon the roll 33 and the end of the strip is passed between the 85 feed rolls 1 and 2 which are being driven by the motor 7. The operation of the feed rolls causes the strip to pass along the groove 21 in the guide 20 and its end then passes between the rolls 26 and 27 and over 90 the bed plate 29 whereupon the revolution of the wheel 18 will cause the striker 19 to contact with the end of the knife 30 causing the same to descend and cut off the strip. It will be noted that when the strip is of some 95 width the knife 30 will be so mounted with respect to the bed plate 29 that the strip will be gradually severed beginning at one edge and extending thereacross. During the time that the strip is being severed by the knife 100

30 the portion between the feed roll 1 and feed roll 26 will buckle as indicated by the dotted line 34 due to the excess material fed during the cutting operation; this excess material is held in place by the guide 21 and rolls 26 and 27, but as soon as the striker 19 has passed beyond the knife 30, the spring 32 raises the knife and the end of the strip is free to move forward whereupon the feed 10 roll 26, revolving at a higher peripheral speed than the pull roll 1, will take up the slack by the time the knife 30 descends again. It will be seen that the length of the portions cut off from the strip 33 will depend upon 15 the number of times the knife 30 is caused to descend in proportion to the rate at which the material is being fed and this proportion can readily be altered by changing the chain drive 17 on the sprockets 14 and 16 20 or by providing a different number of strikers 19 on the wheel 18.

In the modification shown in Figs. 4 and 5, feed rolls 39 and 40 are provided, the roll 40 being mounted in the housing 43 that is 25 pressed downwardly by means of the spring 44. The feed roll 39 is mounted on a shaft 41 which is driven by a motor or pulley 42. The shaft 41 carries a series of sprockets 45 and a sprocket chain 46 from one of the sprockets 45 may drive one of a series of sprockets 47 mounted on a shaft 48 which is parallel to the shaft 41. The shaft 48 carries a striker 49.

A knife carrier 50 is mounted in the guide 33 51 and is provided with springs 52 to tend to maintain the same in an elevated position. The top of the carrier 50 is provided with a buffer 53 and is also provided with an extension 54 which carries a revoluble 40 roll 55. The knife carrier 50 carries a knife 56 which is attached to the carrier 50 by means of the bolt 57 extending through the slot 58. The lower end 59 of the knife 56 may be beveled as indicated so as to cut the 45 material gradually from one edge to the other as the knife is made to descend. A guide 60, provided with a groove 61, extends from the roll 39 to the knife carrier and its end 62 is provided with a sharpened edge to co- 50 operate with the knife 59. An auxiliary guide 63 is provided above and near the rear end of the guide 61.

The operation of this modification is similar to the one described above. This modification is particularly adapted to the cutting of material that is resilient since the resilient material will buckle above the guide 61 and be retained in place by the guide 63 during the descent of the cutter and when the 60 cutter is raised by a spring 52, the resiliency of the material will cause the same to move forward sufficiently during the intervals between the cutting operations. It is obvious that instead of having the striker 49 operate more rapidly by shifting the chain

drive 46, a plurality of strikers 49 may be mounted upon the shaft 48 thus causing the cutter to descend a greater number of times in proportion to the amount of material fed. The shifting of the chain drive obviously 70 might necessitate the use of chains of different lengths.

While the rolls 1 and 6 are referred to as "pull rolls" in the specification, it will be understood that these rolls function to pull the material from the supply roll and thus 75 rolls 1 and 6 constitute a feeding device for feeding the material 33 from the supply roll towards the cutter 30.

I claim:

1. In a cutter, means for continuously feeding a strip of flexible strap-making material, a cutter, means for intermittently operating said cutter at various time intervals to stop and to cut the strap-making material and a guide between said cutter and feeding means adapted to permit the strap material to buckle when the material is stopped by the cutter.

2. In a cutter, means for continuously feeding a strip of flexible strap-making material, a cutter, means for intermittently operating said cutter to stop and to cut the strap-making material, a guide between said cutter and feeding means adapted to permit the strap material to buckle when the material is stopped by the cutter and rotatable means for feeding the material at an increased rate of speed between cutting operations.

3. In a device for cutting a long strip of material into predetermined lengths, pull rolls, a cutter, connections between said pull rolls and cutter whereby the frequency of operation of said cutter with respect to said 105 rolls may be varied, and feed rolls located between said first named pull rolls and said cutter adapted to be continuously driven at a higher peripheral speed than that of said pull rolls and to slidably grip said material. 110

4. In a strip cutter, a continuously operable feeding device, a cutter for momentarily stopping and cutting said strip, a guide between said cutter and feeding means adapted to permit the strip to buckle when the strip 115 is stopped and continuously rotatable means located between said feeding device and said cutter adapted to take up the slack in the strip caused by the buckling of said strip when it is stopped by the cutter.

5. In a strap cutter, in operable succession, continuously operable pull rolls for feeding a strip of material, continuously rotatable feed rolls of greater peripheral speed than the first named rolls adapted to slidably grip 125 said strip, and an intermittently operable cutter.

6. In a strap cutter, in operable succession, continuously operable pull rolls for feeding a strip of material, continuously rotatable feed 130

rolls of greater peripheral speed than the first named rolls adapted to slidably grip said strip, an intermittently operable cutter for stopping and cutting said strip material, and
5 connections between said pull rolls and cutter whereby the frequency of operation of the cutter with respect to the rolls may be varied.

In testimony whereof I affix my signature.
SAMUEL G. MARTIN.
